ABSTRACT: A device for eliminating the thermal instability of a liquid in forced feed convection boilers in which sub-cooled liquids which are introduced at the inlet have a tendency to superheat and flash into vapor to produce liquid slugs which are discharged at the outlet with the dry or superheated vapor. The invention is a rod- or sleeve-type insert located in the heating coils which produces liquid flow damping and controls the liquid superheating, and incorporates a nucleation device or devices disposed axially along the direction of liquid flow and introduces heat dams at the nucleation sites created by vapor from the heated site to prevent the liquid being heated from entering the nucleation site and flashing into vapor.

BOILER INLET PLUG INSERT WITH HEAT DAMS

BACKGROUND OF THE INVENTION

Under certain conditions, liquid forced through heating coils of forced convection liquid boilers with subcooled liquid injected at the inlet and with dry or superheated vapors discharged at the outlet develops severe liquid-boiling heat transfer problems at the localized region or regions in the heating zone where the boiling of the liquid begins. One of these problems is a thermal instability in the liquid caused by the tendency of the heated liquid to superheat and then explosively flash into vapor. This results in liquid slugs separated by large voids of vapor. This pressure pulsing produced by the flashing and the low heat transfer rate due to the dry-heating surfaces in the vapor voids are objectional features.

Superimposed on this phenomenon there can occur a hydrodynamic type of instability due to insufficient damping of the inlet flow.

SUMMARY OF THE INVENTION

The invention is a device to eliminate or control these problems and comprises a rod- or sleeve-type insert, or inserts, located in the heating coils for the liquid which produces flow damping and controls the liquid superheating, increasing the flow resistance in the heating coils by reducing the flow cross-sectional area and increasing the flow velocity. Also the invention provides stabilized nucleation sites located in the heating coils for controlling the thermal instabilities of the liquid resulting from superheating.

BRIEF DESCRIPTION OF THE DRAWINGS

FIG. 1 is a schematic sectional view of a liquid heating unit incorporating the invention.

FIG. 2 is an enlarged sectional view taken through a portion of one of the liquid heating coils, more clearly illustrating the stabilized nucleation site and heat dam unit.

FIG. 3 is an enlarged transverse sectional view taken about on line 3-3 of FIG. 2.

FIG. 4 is a transverse sectional view taken about on line 4-4 of FIG. 2.

FIG. 5 is a similar sectional view through the heat dam unit or insert taken about on line 5-5 of FIG. 2.

FIG. 6 is an enlarged fragmentary longitudinal sectional view taken through the nucleation site opening of the "heat dam" tubular unit.

FIG. 7 is a fragmentary, somewhat schematic sectional view showing a rod type of "heat dam" with nucleation sites and fitted in the heating coil.

FIG. 8 is a fragmentary sectional view taken about on the plane indicated by line 8-8 of FIG. 7, portions being broken away.

Referring to the drawings, and more particularly to FIG. 1 which schematically shows a liquid metal vapor power output unit and boiler incorporating the invention, in which the reference numeral 1 denotes the unit generally, comprising the heating units 2 and 3 and the liquid-heating vaporizing coils 4 and 5 having a subcooled liquid inlet 6 and the vaporized liquid outlet at 7.

Subcooled liquid is supplied to the inlet 6 at a predetermined uniform rate by a suitable pump 8 while the vaporized liquid is discharged at the vapor outlet 7 into and through a suitable engine or turbine 9 having a power "takeoff" shaft 10. After passing through the engine or turbine 9, the vaporized liquid under some predetermined pressure is preferably passed through a suitable condenser or cooler unit 11 of any conventional construction and returned through the conduit 12 to the pump unit 8 where it is again circulated through the heating coils 4 and 5, and vaporized by the liquid heaters 2 and 3 and discharged through the vapor outlet end 7 from the heating coils 4 into the turbine unit 9 to continue to drive the power takeoff shaft 10.

It has been found that under certain conditions, for instance once through forced feed, convection boilers, with subcooled

liquid injected at the inlet and with dry or superheated vapor discharged at the outlet, develop severe boiling heat transfer problems, affecting reliable operations, and these problems are localized in a region in which the boiling begins.

One of these problems is a thermal instability caused by the tendency of the liquid to superheat, and then explosively flash into vapor. This results in liquid slugs separated by large voids of vapor discharged at the vapor outlet 7. The pressure pulsing produced by this "flashing," and the low heat transfer rates due to the dry-heating surfaces in the vapor voids are the objectional features. Superimposed upon this phenomenon there can occur a hydrodynamic type of instability due to insufficient damping of the inlet flow. This is also an objectional phenomenon.

The invention described herein is a device and construction for eliminating or controlling these problems, and comprises rod- or sleeve-type inserts in the heating coils 4 and/or 5, which produce flow damping and control the liquid superheating. The invention increases flow resistance by damping, by reducing the flow cross-sectional area and increases the flow velocity. It also provides stabilized nucleation sites in the liquid heating coils 4 and 5 for controlling the thermal instabilities resulting from liquid superheating. The nucleation devices comprise nucleation sites which are stabilized by means of "heat dams."

Referring more particularly to the schematic sectional view in F. 2, one of these heat dam units is indicated generally at 13 and, as shown in this FIG. of the drawing, is in the form of a tubular insert or sleeve having an inner bore 13' of predetermined diameter for restricting or damping the rate of flow of the liquid being heated between liquid inlet end of the tubular coil 4 or 5 and the heated vapor outlet end 7.

The tubular nucleation and heat dam members, or inserts 13, are suitably inserted and secured in the heating coils 4 or 5 where the heated liquid is superheated to "flash" conditions by the heating units 2 or 3 and tends to explosively flash into vapor, and constitutes nucleation sites 14. The inserts 13 are formed with cylindrical end support portions 15 of suitable length which are in contact with the inner walls 4a of the heating coils 4 or 5 to centralize the tubular heat dam units 13 in the coils and provide heat-conducting means to the inner reduced diameter, tubular portions 16 extending between the spaced heads 15-15 and provide a spaced relation between the inner surface of the liquid heating coils 4 or 5 and the outer surface of the tubular portion 16, to form a "heat dam" or vapor chamber 17 at the nucleation sites 14. This space or cavity 17 is so designed that the liquid vapor interface is both hydrodynamically and thermally stable, and thus provides a "heat dam" at the nucleation sites 14 in which once the liquid in the coils 4 or 5 enters through the nucleation site opening 18, and is first flashed into vapor by the first pressure pulse to fill the chamber 17, this vapor then provides thermal resistance to create a "dam" to the free flow of heat. The result is a "hot zone" which prevents reentry of the liquid into the nucleation site. The hot zone 17 thereby acts as a dam and prevents the repetition of the flashing of the liquid into vapor, which initiated the "heat dam" in the first place. The incorporation of this principle, with a plug-type flow restriction 13, is an important object of the invention.

Nucleation sites in forced convection boilers have been investigated in various laboratories. Roughened surfaces and drilled holes have been used as nucleation sites. In many cases, the sites were not effective because the "flashed" vapor was "washed out" or collapsed, and there was still a need for liquid stabilization in the sites. The employment of the "heat dam" principle of the subject invention has satisfied this requirement, and in addition the inlet flow is stabilized by the plug or sleeve insert 13, incorporating the "heat dam" therein.

The device becomes effective against various instabilities which have been found to plague forced convection boilers. The size of the nucleation site opening and the length of the chamber 17 between the heat dams 13 must be such that the vapor interface maintained in the site or cavity 17 should be

satisfied, and the vapor should not be "washed out" or collapsed due to flow or thermal disturbances. When the boiler is started, a single "pulse" due to superheat is produced, in the liquid in the dam chamber 17, and this forms the vapor within the site. If this vapor is ejected or collapsed (condensed), the pulses will become repetitious thereby creating the objectionable thermal instability. Some superheat in the vapor should, of course, be maintained to prevent the collapse of the vapor in the cavity 17 as a result of the pressure pulse.

Referring to the sectional views shown in FIGS. 7 and 8, the reference numeral 20 denotes a portion of the liquid heating and vaporizing coil, for instance, at the location where the boiling of the liquid begins to take place. The portion of the coil is shown straight for a better illustration thereof. The "heat input" means is omitted but comprises a suitable surrounding superheating unit to promote boiling and comprises heat transfer means for heating the liquid and superheating the vapor produced by the vaporization of the liquid, for instance, similar to heaters 2 and 3 in FIG. 1.

The reference numeral 21 denotes a rod-type insert which produces flow damping and controls the liquid superheating and increases flow resistance (damping) by reducing the flow cross-sectional area and increasing the flow velocity, and also provides stabilized nucleation sites for controlling thermal instabilities resulting from liquid superheating.

In the drawing the reference numeral 23 denotes the central stem portion of the rod insert having the spaced heat transfer shoulders 24 and 25 with the liquid flow passage 26 located therebetween.

Nucleation sites are indicated at 27, which extend across the heat transfer shoulders 24 and 25 from the liquid conducting flow passage 26 into the vapor chamber 28, which provides a heat dam cavity between the enlarged portion 29 of the stem or rod 21 and the walls of the heat transfer shoulders 24 and 25 at the opposite sides of the vapor collection cavity 28.

The "heat dam" cavity 28 provides a liquid vapor interface that is both hydrodynamically and thermally stable. Some superheat in the vapor is maintained in the cavity 28 to prevent collapse of the vapor in the cavity as the result of the initial pressure pulse. The vapor itself causes a resistance to the heat flow, thus raising the temperature of the surface and vapor. The amount of superheat for a stable "heat dam" can be estimated by means of the well known Clausius-Clapryron relation.

The effect of the heat dam is created by vapor formed by the first pressure pulse and flashing of the superheated liquid in the cavity 28 into vapor. After this the vapor thermal resistance in the cavity 28 creates a "dam" to the flow of heat. The result is a hot zone which prevents the reentry of the liquid from the flow passage 26 into the nucleation sites 27. The hot zone thereby prevents the repetition of the flashing of the liquid into vapor which initiated the "heat dam" in the first place. The incorporation of this principle, as explained, with the "plug" type restriction, as previously mentioned, is the basic invention.

For purposes of exemplification of the invention, a particular embodiment of the invention has been shown and described to the best understanding thereof. However, it will be apparent that changes and modifications in the arrangement and construction of the parts thereof may be resorted to without departing from the true spirit and scope of the invention as defined in the accompanying claims.

I claim:

1. In a liquid superheating and vaporizing device, liquid superheating and vaporizing coil means having a subcooled inlet and a superheated liquid vapor outlet and heating coil means between said inlet and said outlet for heating and vaporizing liquid in said coil means intermediate said inlet and said outlet, said liquid heating and vaporizing coil means having a nucleation site therein where boiling of said liquid begins and tends to explosively flash into vapor, a "heat dam" insert unit in said coil means enclosing said nucleation site having a restricted liquid flow passage between the ends thereof, in-

cluding spaced heat-conducting means in contact with the inner surface of the heating coil means having a closed "heat dam" cavity therein located between said spaced heat conducting means and the inner surface of said liquid heating and vaporizing coil means and the outer surface of said insert, and in surrounding relation to said nucleation site, said insert having a restricted liquid receiving opening therethrough between said liquid flow passage and the interior of said heat dam insert cavity for trapping and confining vapor of boiling liquid in said cavity at said nucleation site to reduce heat transfer in said cavity between said heating coil means and the liquid at said site and increasing the rate of liquid flow past said site, to prevent the liquid at said site, heated by said coil means, from explosively flashing into vapor during the flow of the liquid past said nucleation site.

- 5 2. In a liquid-superheating and -vaporizing device as set forth in claim 1 in which said heat dam insert comprises an elongated cylindrical member having longitudinally spaced heat transfer portions adapted to be disposed in said heating coil means in heat transfer contact relation with the inner surface of said heating coil means at opposite sides of the nucleation site in the heating coil means, said heat dam unit having a smaller diameter elongated central portion between said end portions to form a "heat dam" cavity between said end portions and the inner surface of said heating coil means and said smaller diameter elongated central portion, said heat dam insert having an elongated restricted central liquid flow passage therethrough between said spaced heat transfer portions to conduct liquid in said heating coil means through said insert at an accelerated flow rate, said heat dam insert having a restricted vapor outlet therein communicating between the interior of said "heat dam" cavity and said restricted liquid flow passage, for initially trapping and discharging heated liquid vapor from said heat dam cavity into said central liquid flow passage and resisting entrance of liquid from said flow passage into said heat dam cavity, for lowering heat transfer at said nucleation site between said heating coil means and liquid in said central liquid flow passage passing said nucleation site.
- 10 3. In a liquid-superheating and -vaporizing device as set forth in claim 1 in which said "heat dam" insert comprises a tubular member having a central restricted liquid flow passage therethrough, longitudinally spaced cylindrical heat transfer wall members disposed in heat transfer relation with the inner surface of said heating coil means and connected to each other by a smaller diameter tubular connecting member having said restricted liquid flow passage therethrough, to form an elongated heat dam cavity between said cylindrical heat transfer wall members and the inner surface of said heating coil means and the outer surface of said smaller diameter tubular connecting member, said tubular member having a restricted vapor vent passage therein extending from said heat dam cavity into said restricted liquid flow passage, for trapping liquid vapor from boiling liquid in said heat dam cavity, to prevent liquid in said liquid flow passage from entering through said vapor vent passage into said heat dam cavity, said heat dam insert adapted to be disposed in said heating coil means to surround a nucleation site in the heating coil means, and reduce transfer of heat at said nucleation site between the heating coil means and the liquid in said liquid flow passage, to prevent said liquid from reaching said nucleation site and explosively flashing into vapor between said nucleation site and the superheated vapor outlet in said heating coil means.
- 15 4. In a liquid-superheating and -vaporizing device as set forth in claim 1, in which said heat dam insert comprises an elongated rod-type insert adapted to be inserted in said heating coil means having a restricted liquid flow passage extending between the ends thereof, spaced elongated heat transfer wall members projecting outwardly at opposite sides of said liquid flow passage, between the opposite ends of said insert and adapted to be disposed in heat transfer relation with the inner surface of said heating coil means, said insert having an enlarged central stem member between said heat transfer wall members having a smaller diameter than the transverse inner

diameter of said heating coil means, to form a heat dam cavity in said insert between said central stem member, the inner surface of said heating coil means, and said outwardly projecting heat transfer wall members, adapted to enclose a nucleation site in said heating coil means, a restricted vapor vent passage in said insert extending across said heat transfer wall members in restricted communication between the interior of said heat dam cavity and said liquid flow passage, whereby said heat dam cavity in said insert surrounding said nucleation site is adapted to trap liquid vapor from boiling liquid in said heating coil means at said nucleation site and restrict the inflow of liquid in said flow passage from entering said heat dam cavity and explosively flashing into vapor at said nucleation site.

5. A liquid-superheating and -vaporizing device as set forth in claim 4 in which said spaced elongated heat transfer wall members extend helically from end to end of said insert in

uniform spaced relation around said enlarged central stem portion with said restricted liquid flow passage extending helically around said central stem member between said helically extending spaced elongated heat transfer wall members, to 5 provide a heat dam cavity helically surrounding said central stem member, between said helical wall members and said enlarged central stem member and the inner surface of said heating coil means, extending across said nucleation site in the heating coil means where liquid in said heating coil means 10 begins to boil and tends to explosively flash into vapor, and a restricted venting passage in said helical dam cavity opening into said helical liquid flow passage between said spaced helical wall members, for restricting the inflow of liquid from said helical liquid flow passage into said helical heat dam cavity by 15 the vaporized liquid in said heat dam cavity.
